UNITED STATES PATENT OFFICE.

HARRY A. THUNEMAN, OF ST. LOUIS, MISSOURI.

VACUUM-SEPARATOR.

1,281,881.

Specification of Letters Patent. Patented Oct. 15, 1918.

Application filed March 16, 1917. Serial No. 155,183.

To all whom it may concern:

Be it known that I, HARRY A. THUNEMAN, a citizen of the United States of America, and a resident of the city of St. Louis and State of Missouri, have invented certain new and useful Improvements in Vacuum-Separators, of which the following is a specification.

The primary object of this invention is to provide an improved separator for crushed or pulverized materials such as slate, limestone, coal, mineral ores, etc., in which the conveying means relative to conveying the material through the separator is brought about by the production of a vacuum, and in which an improved regulating mechanism is made co-operative with the air currents that are produced by the created vacuum so that the resultant product, which is allowed to pass through the separator will be of a grade of the desired fineness.

Other and further objects will appear in the specification and be specifically pointed out in the appended claims, reference being had to the accompanying drawings exemplifying the invention, and in which:

Figure 1 is a vertical section of this improved separator, an intermediate portion thereof being broken away.

Fig. 2 is a horizontal section taken on the line II—II of Fig. 1.

Fig. 3 is a horizontal section taken on the line III—III of Fig. 1.

Fig. 4 is an enlarged fragmentary section taken on the line IV—IV of Fig. 1.

Fig. 5 is an enlarged fragmentary section taken on the line V—V of Fig. 2.

Referring to the drawings, 1 designates an outer casing, having an air-tight top 2, said casing being preferably of a tubular construction, and having its lower end 3 converging into a pipe formation so as to connect with the pipe 4, said pipe being in communication with an exhaust fan 5 which is driven by the pulley 6.

Leading from said fan 5 is a discharge pipe 7. Located in the casing 1 and held at a distance from the circular wall thereof by supporting brackets 8 is a hopper 9, and leading from the bottom of said hopper and passing through the inclined wall of the lower end 3 of the casing 1 is a discharge pipe 10. Embracing the upper end 11 of pipe 10 is the hopper 9 and surrounding the outer wall thereof is one end of a telescoping member

12, said member 12 being slidably related to the upper end of said hopper 9, and slidably related to the upper end of said telescoping member 12 is another telescoping member 13. These telescoping members can be of any desired number, the uppermost telescoping member bearing a cross bar 14.

Concentrically arranged in and adjacent the upper end of the hopper 9 and supported thereto by a plurality of braces 15, is an open ended receiving member 16, said member 16 comprising a pair of frustums, one of which is inverted, the base portion of the lower frustum adjoining the base portion of the upper frustum.

Concentrically arranged in said receiving member 16 is a combined upwardly and downwardly deflecting member 17, said deflector being supported from said member 16 by the braces 18 and being additionally supported by the vertically arranged support 19 which is suspended from the top 2. Transversely arranged adjacent the upper end of the receiving member 16 is a shaft 20, and secured to said shaft are a pair of sprockets 21, each of said sprockets having an endless chain 22 mounted thereon, each of said chains having their upper ends engage a respective sprocket 23, said sprockets 23 being mounted on a horizontally arranged shaft 24 which is supported by the bearings 25 that are suspended from the top 2. One end of the shaft 24 extends through the wall of the casing 1, said extended end having a crank 26 secured thereto. Each of the chains 22 are secured to the cross bar 14 which is carried by the upper telescoping member 13, as designated at 27.

Extending into the lower end of the member 16, and being in concentric relation with the deflector 17 is an intake pipe 28, and secured to said pipe adjacent the upper end thereof is a spreader 29. This pipe 28 extends through the walls of the hopper 9 and lower end 3 of the casing 1, and is adapted to lead from a pulverizing device, said pipe serving as a conveyer from the pulverizer to the separator.

In the operation of this improved separator, the intake pipe 28, as afore related, being in communication with a pulverizer, will serve as a conveyer for the pulverized products when the suction fan 5 is put in operation, as air will be entrained through said pipe 28 into the receiving member 16, through the plurality of telescoping mem-

bers, then down the vertical passageway 30 which surrounds the telescoping members through pipe 4 into the fan 5 and discharged through the discharge pipe 7.

- 5 As the pulverized products emerge from the pipe 28 along with the air current entrained therethrough, the same will strike against the deflecting member 17, thereby throwing the pulverized products out-
10 wardly, and inasmuch as the diametric area of the receiving member 16 is greater than the diametric area of the pipe 28, the carrying forces of the discharged air current from the pipe 28 will be somewhat weakened, in
15 which the heavier particles of the pulverized product will fall downwardly on account of the fact that the created air force is not great enough to carry them farther, said heavier particles falling through the open-
20 ing 31 of the receiving member 16, into the hopper 9 and discharging through the pipe 10. The lighter particles of the pulverized product will be carried on upwardly, out of the receiving member 16, and into the plu-
25 rality of telescoping sections 12, and inasmuch as the diametric area of said telescoping sections is greater than the diametric area of the receiving member 16, the coarser or heavier pulverized particles that are then
30 left, after the same has reached the sections 12, will fall downwardly and pass through the circular passageway 32, which is formed between the member 16 and the upper end 11 of the hopper 9, and finally depositing in the
35 discharge pipe 10. The finer particles of the pulverized product will be forced on upwardly and over the top of the uppermost telescoping section 13 and be entrained in the passageway 30 which is formed between the
40 casing 1 and the outside walls of the telescoping sections 12 and 13, said passageway leading to the pipe 4, through the exhaust fan 5, and finally discharged through the discharge pipe 7 to a depositing receptacle, (not shown).

From the aforesaid description of this improved separator, it is self evident that the forces of the entrained air currents from the pipe 28 will diminish more and more as they are extended into larger areas. It is therefore seen that the air currents will not have the lifting volume relative to the pulverized particles when said air currents reach a plane adjacent the uppermost telescoping section 13, as against the forces of said air currents when said air currents were on a plane adjacent the lowermost telescoping section 12. In this connection, attention is called to the collapsible nature of the telescoping sections, in which the total length of all the sections can be reduced to any required length by the manipulation of the shaft 24, which when operated on by the crank 26 and turned in a left hand direction, will force the uppermost section 13

downwardly, said uppermost section in turn forcing each succeeding section downwardly, on account of the fact that the chains 22, relative to the sprockets 21 and 23, respectively, are secured to the cross bar 14, thereby decreasing the distance from the receiving member 16 and the point of communication with the passageway 30.

From the aforesaid it is to be seen that coarser pulverized materials can be carried on upwardly and discharged over the uppermost section 13 into the passageway 30, along with the finer particles, whereas if the telescoping members are extended so that the uppermost section 13 will be at a greater distance away from the receiving member 16, the force of the air currents will not be great enough to lift the coarse particles, but will only be of such a force whereby the finer particles will be carried over the upper section 13, thereby depositing only the finest of material into the receiving receptacle.

In a device of this improved character, it is essential that the compartment comprised in the casing 1 be air tight, the source of intake being through the pipe 28 only. In this connection, an air trap as designated by 33 is located in the discharge pipe 10.

The coarser particles of pulverized material which were allowed to fall into the hopper 9 and discharge pipe 10 are adapted to be conveyed through said pipe 10 to the pulverizer, not shown, to be reground. In order to provide means for preventing the sections 12 and 13 from being pulled apart, an inner 100 ring 34, which is carried by the lower end of the upper section 13 and by the lower ends of each succeeding section 12, are adapted to coöperate with respective outer rings 35, which are carried on the outside of the upper 105 end of each section 12, (see Fig. 5).

What I claim is:

1. A separator comprising a closure, an outlet for said closure, a telescoping member located in said closure and a material feed 110 pipe leading to the lower end of said member.

2. A separator comprising a closure, an outlet for said closure, a reducibly mounted sleeve-like member located in said closure, a suction material pipe leading to the lower end of said member, and means whereby a 115 vacuum is created through said member.

3. A separator comprising a closure, a reducibly mounted sleeve-like member located 120 in said closure, an inlet passageway for feeding material to the lower end of said member, and an outlet passageway leading from the upper end of said member.

4. A separator comprising a closure, a 125 telescoping member located in said closure, and an inlet material passageway leading to the lower end of said member, and a deflecting member located above said passageway.

5. A separator comprising a closure, a telescoping member located in said closure, a feed conveyer passageway leading to the lower end of said member, a deflecting member located above said passageway, means for reducing said telescoping member, and an outlet passageway leading from said telescoping member.

6. A separator comprising a closure, a
10 sleeve-like member comprised of a plurality of telescoping sections located in said clo-

sure, means for extending said sections of said member, a receiving member concentrically arranged relative to one of said sections, a receiving and discharging funnel secured to the lower one of said sections, and a feed conveyer pipe leading to said lower section.

HARRY A. THUNEMAN.
